AUTOMATIC GRINDING MACHINE

John F. Pelton, Kenmore, N. Y., assignor to Union Carbide and Carbon Corporation, a corporation of New York

Application June 25, 1951, Serial No. 233,375

21 Claims. (Cl. 51—103)

1

This invention relates to an improved grinding machine for automatically feeding, grinding and ejecting a series of blanks. More particularly, the invention concerns a fully automatic machine for grinding points on tiny blanks of a hard material such as sapphire or ruby to form styls such as phonograph needles.

Corundum crystals in the form of ruby and sapphire have been used as points in composite phonograph needles for some time. Until recently such needle points were relatively large, and easy to handle in a grinding operation. However, at the present time phonographs employ tiny corundum needle points as small as .05 inch long and .016 inch in diameter, having 45 degree symmetrical conical tips. Such tiny work-pieces have magnified the difficulties of grinding this hard material, and have made it difficult to obtain needle points which are uniform and symmetrical in shape, which are accurately dimensioned, and which are otherwise of high quality.

Fully automatic grinding machines constructed in accordance with the present invention have made it possible to produce tiny corundum phonograph needle points rapidly and economically, and with the important attributes outlined above. Such a machine, which is to be described in detail below, acts automatically to perform the following functions in grinding needle points:

A. A series of tiny cylindrical blanks is fed, one at a time, onto a longitudinal support at a feeding station near one end of the support.

B. The blank is advanced longitudinally along the support to a position just short of head-on contact with a rotating grinding wheel which is positioned at a grinding station adjacent the opposite end of the support.

C. The blank is thereafter advanced into initial contact with the grinding wheel and, as grinding of the blank proceeds, it is progressively advanced longitudinally an accurately measured amount toward the grinding wheel so that the latter grinds a complete conical point.

D. The blank is rotated rapidly on a fixed longitudinal axis while in contact with the grinding wheel.

E. Upon completion of the grinding operation the grinding wheel is automatically retracted from the grinding station, rotation of the point is stopped, and the point is ejected.

F. Then the next blank in the series is fed upon the longitudinal support, the grinding wheel is returned automatically to the grinding station, and the above operations are repeated.

G. In the event that a blank becomes jammed

2

before being fed onto the support, the machine is automatically stopped.

H. The operations described above in paragraphs A to G are controlled synchronously in timed relation to one another by interlocking cams cooperating with the several functioning mechanisms.

One embodiment of the automatic grinding machine of the invention will be described in detail below to illustrate the principles involved. However, it is to be understood that changes in the construction and in the relative arrangement of parts can be made within the spirit of the invention.

mechanism of Fig. 1, showing the position of parts during actuation thereof;

Fig. 14 (on the same sheet as Fig. 1) is an end elevational view of a part of the machine as seen from the left in Fig. 1;

Fig. 15 (on the same sheet as Fig. 2) is a perspective view of a part of the blank-feeding mechanism;

Fig. 16 is a diagram showing development of the cam contours for synchronizing the functions of the grinding machine; and

Fig. 17 is a pictorial electrical diagram of the machine.

GENERAL DESCRIPTION

Generally in accordance with the invention, the automatic grinding machine comprises a platform P carrying a longitudinally extending horizontal work support S upon which a cylindrical blank is fed and is held during the grinding operation. A blank to be ground is fed laterally onto the support S by a blank-feeding mechanism F located at a feeding station near one end of support S, and then is advanced along the support S by a longitudinally movable advancing device A which pushes the blank into position adjacent a grinder G located at a grinding station at the opposite end of support S.

At the grinding station the blank is rotated on a fixed longitudinal axis by suitable rotating mechanism R, such as a pair of rolls R₁ and R₂ located on opposite sides of the support S and rotating in the same direction on longitudinally extending axes. After its initial positioning adjacent the grinder G, the blank is fed progressively forward a short and accurately measured distance by a micrometer feed mechanism M cooperating with the advancing device A, so that the point can be completed.

Upon completing the grinding operation the grinder G is automatically retracted away from the support S, the rolls R₁ and R₂ are stopped, and the needle point is ejected forwardly from the support by ejecting mechanism E, which constitutes a part of the advancing device A and which acts by a sharp longitudinal blow upon the latter to eject the blank.

After ejection of the ground point the advancing device A returns rearwardly along the support S to the feeding station to receive from the blank feeder F the next blank to be ground. During its return motion the advancing device A engages the blank-feeding mechanism F and causes the latter to feed a blank laterally onto the support S after the advancing device has cleared the feeding station.

All of the above described mechanisms are operated synchronously in timed relation to one another by a suitable cam control C which is located near the bottom of the platform P.

Fig. 5 shows a needle point 8 produced as described above.

SPECIFIC DESCRIPTION

Platform P

The platform P for supporting the various operating members of the grinding machine comprises a horizontal upper shelf 11 for the blank-manipulating and grinding apparatus supported by four pillars 13, and a horizontal lower shelf 15 for the cam control mechanism C.

Work support S

The longitudinal work support S comprises a horizontal bedplate 17 mounted on the top of

the upper shelf 11. A longitudinal channel 19 (see Fig. 10) for a blank is formed on the top of bedplate 17 by three side plates 21, 22 and 23, the side plate 21 extending substantially the full length of the bedplate, the side plate 22 terminating at its rear end short of the rear end of the bedplate and adjacent the forward edge of the blank feeder F, and the side plate 23 continuing from side plate 22 past blank feeder F and having a tongue 24 (see Fig. 11) which bridges the outlet from F.

A thin work rest blade 25 is removably and replaceable clamped by a spring finger 26 in a recess on the side of bedplate 17 near its front end. The top surface of blade 25 is flush with the bottom of channel 19 and located between the rolls R₁ and R₂ to support a rotating blank during the grinding operation.

Grinder G

The grinder G comprises a grinding wheel 29 stationed adjacent the front end of the work support S with its peripheral grinding surface 27 arranged head-on to the support. Grinding wheel 29 is mounted on one end of a horizontal axle 31 which extends transversely of and normal to support S and is spaced both longitudinally of and transversely above the top surface of work rest blade 25 and above the rotational axis of the blank to be ground, so that the peripheral grinding surface 27 sweeps downwardly and forwardly between rolls R₁ and R₂ across the front end of a blank to form a point thereon, as shown diagrammatically in Fig. 4.

The grinding wheel axle 31 is journaled in a bearing 33 carried on the rear side of a table 35 which is mounted on an upright bent post 37 and held in place by a set screw (not shown). Fine adjustment of the grinding wheel assembly up and down on the post is secured by a bolt, cap, and spring assembly 38. The other end of axle 31 protrudes from bearing 33 and carries a pulley 39 driven by a belt 41, which in turn is driven by an electric motor 43 mounted on the front of table 35 on the side of post 37 opposite bearing 33.

Post 37 extends down through an oversized aperture 45 in upper shelf 11 to a horizontal shaft 47 which is pivoted at its ends on a pair of pivot pins 49, as shown in Fig. 7.

The weight of the driving motor 43 and its position on the table 35 are such that the weight of the grinding wheel 29 is overbalanced and the post 37 is normally urged in a forward and downward direction to withdraw the grinding wheel from its grinding station adjacent support S. At any given moment the position of the grinding wheel is governed by a cam surface 50 of a flanged circular control cam 51 rotating with a cam shaft 53 which is journaled in a pair of spaced pillow blocks 55 on the lower shelf 15. Cam shaft 53 is driven by an electric motor 56 acting through a suitable sprocket, chain, worm and gear train 58. A lever arm 59 projects downwardly from the pivot shaft 47 and carries a cam follower 57 which is held against the cam surface 50 by the weight of the grinder motor 43 and follows the contour of the cam surface as the latter rotates, thus moving the grinder into and out of grinding position.

Cam follower 57 is carried on a leaf spring 60 which is secured at its upper end to the arm 59 and is urged strongly toward the arm by the spring action. An adjusting screw 62 separates arm 59 and spring 60 by an amount which

is so adjusted that the grinder G engages stop 61 slightly before cam follower 57 reaches the highest point on cam 51. Further motion of the cam follower then flexes spring 60 and lifts the adjusting screw 62 from arm 59, forcing grinder G against the stop 61 with a definite controllable force, thus avoiding the need for extremely precise adjustments in the system.

The surface 50 of grinder cam 51 is so shaped that during the major portion of its rotation the cam follower 57 is in contact with the high portion of the cam, as shown at *a* in Fig. 16, and the grinding wheel 29 is held at its grinding station adjacent the support S while the grinding of a blank proceeds. After a time interval determined by the rotational speed of cam 51, when grinding has been completed, the cam follower 57 enters the low portion *b* of the cam and the grinding wheel is retracted from its grinding station to permit the ground blank to be ejected. The cam follower remains in the low portion *b* until the next blank is positioned at the grinding station, whereupon the high portion *a* reengages the cam follower and restores the grinding wheel to its grinding station. The proper adjustment of the grinding wheel at the grinding station is accomplished by adjustable stops 61 carried by a bracket 63 on the top of the machine.

As a safety feature cam 51 has a radial pin 52 which can enter a slot 54 in arm 59 and act to pull the grinder from its grinding station if frictional forces or other obstruction should prevent the grinder from falling back by gravity. In normal operation the pin 52 never touches any part of arm 59.

For grinding the tiny corundum phonograph needle points for which this machine is particularly adapted, an extremely thin grinding wheel 29 is required. One type of wheel which has been found satisfactory is a metal-bonded diamond wheel three inches in diameter and 0.009 inch thick at its peripheral grinding edge 27.

Mechanism R for rotating blank during grinding

A symmetrical point is ground on the end of a blank by rotating it rapidly on a fixed longitudinal axis during grinding. Rotation is accomplished by the pair of driving rolls R₁ and R₂ which are located on opposite sides of the support S at the grinding station adjacent the front end of the support. Both rolls are driven in the same direction by longitudinally extending axles 65 and 67 which are journaled in and project rearwardly from bearing blocks 71 and 69, respectively (see Fig. 8 detail). Both axles 65 and 67 are in turn driven by a chain 77 running from an electric motor 79 to a pair of sprockets 73 and 75 on the rear ends of the axles. Sprocket 75 has a smaller pitch diameter than sprocket 73 so that the roll R₁ rotates at a higher peripheral speed than roll R₂, even though its diameter is less than R₂, to hold the blank down on the work rest blade 25 during grinding.

The roll R₁ has a peripheral surface 81 of rubber or a similar resilient gripping material. The other roll R₂ is formed of a hard metal such as steel. The axle 65 of the rubber-covered roll R₁ is horizontal but the axle 67 of the steel roll R₂ is tilted downwardly and rearwardly at a small angle such as three degrees to maintain a blank in constant contact with the end of advancing device A while the blank is being ground. Both rolls dip into oil reservoirs such as that shown at 80 in Fig. 8. This oil is carried up to the

point of grinding to serve as a coolant and lubricant.

The rolls R₁ and R₂ are arranged with opposed peripheral surfaces which pass close together and close to the sides of the work rest blade 25, the top of which is about level with the common diameter of the two rolls, as shown in Fig. 4, to support a blank 83 in the throat 85 between the two rolls just above the common diameter.

The roll driving motor 79 is controlled synchronously with grinder G by a switch 87 (see Figs. 1 and 17) which is actuated by a finger 89 on grinder pivot shaft 47. When the grinding wheel 29 is retracted from its grinding station, the finger 89 opens switch 87 to stop motor 79 and rolls R₁ and R₂. When the grinding wheel is restored to its grinding station in the manner previously described the finger 89 permits the switch 87 to close and starts the motor 79 and rolls R₁ and R₂.

Blank advancing mechanism A

A blank 83 is placed upon the longitudinal work support S in alignment with the channel 19 when the advancing device A is in its fully retracted position (as shown in Fig. 10). The advancing mechanism A comprises a long push rod 91 which passes at its rear end through a bore in an upstanding bracket 93, and has an intermediate portion passing through a bore in a block 95 near the middle of platform P. Push rod 91 is held in its retracted position by a yoke 97 carried on the upper end of an upright lever 99 having a pivot 101 at its lower end, the yoke being captured between two sets of abutment nuts 100 and 102 adjustably threaded on the push rod. A cam follower 103 between the ends of lever 99 is held by a spring 104 in constant contact with a circular flanged cam 105 which rotates with cam shaft 53. Cam follower 103 acts to retract the push rod 91 when on an ascending portion 107 of the cam, holds the push rod in fully retracted position momentarily (as shown in Fig. 10) when on a peak portion 109 of the cam, and permits the push rod to advance along the support S to carry the blank 83 from the feed station to the grinding station while on a descending cam portion 111.

As the cam follower 103 traverses the descending portion 111 of cam 105 a coil spring 113, which is compressed between the bracket 93 and an annular hollow flange 115 forming a part of the push rod, urges the push rod forward along support S. The bottom of flange 115 is keyed in a longitudinally slotted base plate 118 to prevent turning of the push rod 91 during its movement back and forth. The front end of push rod 91 engages the blank 83 shown in Fig. 10, and pushes it along the channel 19 into throat 85 between the two rolls R₁ and R₂, the movement of the blank being stopped when a shoulder 114 on the push rod abuts against a hollow bushing 116 surrounding the push rod and threaded into block 95. The rotating grinding wheel 29 then is lifted into position at the grinding station by cam 51 and at the same time the switch 87 is actuated to start the rolls R₁ and R₂ so that the blank revolves rapidly on a fixed longitudinal axis just out of contact with the peripheral grinding surface of the grinding wheel.

Micrometer feed mechanism M

Immediately after grinding wheel 29 reaches

the grinding station, the blank is advanced into initial contact with the grinding wheel by the micrometer feed mechanism M which moves the blank slowly forward into the grinding wheel thereafter. Mechanism M is actuated by a cam 117 (see Fig. 6), including an ascending portion 125 which moves a free end 123 of a lever 119 downwardly about a fixed pivot 121, a peak portion 127, and a descending portion 129 which permits the end 123 of lever 119 to rise under the influence of coil springs 131. Springs 131 are stretched between a stationary cross bar 133 near the top of the machine and a vertically movable lower cross bar 135, the latter being coupled to the movable end 123 of lever 119 by an adjustable coupling 137. Coupling 137 includes a socket member 136 pivotally secured to lever 119, and a plug member 138 pivotally secured to cross bar 135 and slidably adjustable in the socket member, the position of the plug being fixed by 20 set screws.

Cross bar 135 also carries an upwardly extending vertical rack 139 which is slidable in a vertical guide 141 on the side of platform P. Rack 139 engages a pinion gear 143 on one end of a horizontal shaft 145 which is journaled in a bearing 147. Shaft 145 projects to a position above the support S and carries a helical gear 149 which meshes with a helical gear 151 mounted on the hollow bushing 116. Gear 149 is secured to shaft 145 by a set screw which can be loosened to permit the gear to be rotated freely to adjust the apparatus for different blank lengths and to compensate for wear.

After the initial contact of blank 83 with the grinding wheel 29 the descending portion 129 of cam 117 permits the rack 139 to rise, thus operating the helical gear 151 so that the hollow bushing 116 screws into the counterbore 155 and allows the push rod 91 to advance slowly toward the grinding wheel under the force of the spring 113, to complete the grinding of a symmetrical point on the blank.

Blank ejection mechanism E

Upon completion of the needle point the cam 51 permits the grinding wheel 29 to be retracted from the grinding station, and at the same time the finger 89 actuates the switch 87 to stop the rolls R₁ and R₂. Immediately thereafter a wedge-shaped lug 157 on the peripheral surface of the advancing-mechanism cam 105 passes between a second cam follower 159 on the lever 99 and a cam follower 161 projecting from a second upright lever 163, which is also pivoted at its lower end 165 (see Fig. 14). The lug 157 separates the two levers against the resistance of a spring 167 and withdraws the yoke 97 a short distance toward abutment nut 100. Lug 157 releases cam follower 159 while still engaging cam follower 161, thus permitting lever 99 and yoke 97 to move forward rapidly and strike the abutment nut 102 a sharp blow to move push rod 91 a short distance longitudinally forward against the pressure of a coil spring 171 within the hollow flange 115, thus impelling the ground blank forwardly from the work support. Immediately thereafter the lug 157 releases cam follower 161 and permits lever 163 to return to its original position. This construction permits spring 167 to impart a strong force to lever 99 just before and during blank ejection, when it is most needed, yet to be completely inoperative during the major portion of the cam's revolution.

Blank feed mechanism F

Immediately after a ground point has been ejected from the support S the ascending portion 107 of advancing mechanism cam 105 forces the yoke 97 to engage abutment nut 100 and pull the push rod 91 rearwardly away from the grinding station to the position shown in Fig. 10 to leave the feed station clear for introduction of the next blank from the feeder F, at the same time compressing the coil spring 113.

Meanwhile the ascending portion 125 of micrometer feed cam 117 depresses the lever 119, causing rack 139 to rotate pinion 143 reversely, thereby withdrawing bushing 116 from counterbore 155 and restoring it to its original position where it can serve as a stop for the push rod 91.

During the rearward stroke of push rod 91 a laterally projecting flexible spring finger 175 on top of the flange 115 engages a hook 177 on the free end of an actuator-arm connecting rod 179 which extends longitudinally rearwardly from a crank arm 181, the latter being mounted on a vertical shaft 183 which is journaled in a feed block 185 located in a recess between the bearing block 69 and the bedplate 17. Connecting rod 179 is connected to crank arm 181 by a coupler 186 slidably adjustable along the rod, and having a vertical pin 188 positioned within a slot 190 in the end of the crank arm.

During its rearward motion the connecting rod 179 compresses a spring 187 between a lug 189 and a cam block 191. At the same time, the rod rotates the shaft 183 to turn an eccentric spud 193 on the lower end thereof which works in a groove 195 in a blank pusher or feed slide 197, causing the latter to move transversely away from the bedplate 17 against the spring pressure of a safety switch 233 acting through a push rod 237 and a lever 235 (all to be described in detail hereinafter) to permit the next blank 199 to be fed forwardly from a tube 201 onto a table 203. Table 203 projects transversely into a slot in bedplate 17 and has a top surface level with the surface of the bedplate, thus in effect constituting a part of the bedplate.

When the push rod 91 has been almost fully retracted, the finger 175 rides up an inclined cam surface 207 (see Fig. 15) which flexes the finger and raises it out of engagement with the hook 177. Thereupon the force of the compressed spring 187 restores the connecting rod 179 to its original forward position with hook 177 against a stop 208, thus actuating the crank arm 181 and shaft 183 to permit the spring pressure of safety switch 233 to move the feed slide 197 toward the bedplate 17 so that a tongue 209 on the slide pushes the next blank 199 along the table 203 into the path of the push rod 91. At the same time the tongue 209 obstructs the outlet 213 of tube 201 and prevents the passage of another blank onto the table 203. Slot 195 is made wide enough so that eccentric pin 193 cannot push slide 197 forward if it should become jammed by a blank.

The push rod 91 then advances the blank 199 to the grinding station and the various operations are repeated, all as described previously herein.

Blanks are supplied one at a time to the table 203 through the long thin tube 201 having its outlet 213 adjacent the table 203 in position to discharge the blanks thereon and against a stop 205. The tube 201 has an inlet 215 (see Fig. 3) at its opposite end enclosed by a hollow block 217 whose open end is provided with a cap 219 to

form a chamber 221 adjacent the inlet. A series of blanks is introduced into the tube 201 in end-to-end relation by removing the cap 219 and passing the blanks through the inlet 215. The cap 219 is then replaced and the blanks are fed through the tube by supplying a fluid such as air or oil under pressure to the chamber 221 through a supply tube 223. Tube 201 is encased in a second tube 202 which protects the former by preventing kinking and other damage.

Electrical controls

The several electric motors 43, 56 and 79 for driving the mechanisms described above are controlled by manual switches 225, 227 and 229 shown in Fig. 17. Grinder motor 43 and cam shaft motor 56 operate continuously when the machine is in normal use. Roll-driving motor 79 is started and stopped automatically by the switch 87 (Figs. 1 and 17) in accordance with the position of the grinder G. Motors 56 and 79 are provided with magnetic brakes to stop them quickly when the power is disconnected.

The machine is also provided with a pair of parallel-connected synchronized safety switches 231 and 233 in circuit with the cam-shaft-driving motor 56, which act to stop the cam shaft if a blank becomes jammed in the feeding mechanism F and cannot be pushed onto the bedplate 17 by the slide 197. The operation is as follows:

(a) While a blank is at the grinding station the feed slide 197 is in its forward position as shown in Figs. 9 and 10 and a vertical switch lever 235, which is pivoted at its lower end at 236, acts through a horizontal push rod 237 to allow the spring-actuated safety switch 233 to be in its normally closed position so that the cam shaft motor 56 operates. At the same time the low part 240 of a cam 239 on the cam shaft 53 allows the second spring-actuated switch 231 to be in its normally open position.

(b) When the feed slide 197 moves to its rearward position preparatory to feeding the next blank onto the bedplate 17, it operates switch lever 235 to open switch 233 against its spring pressure. Before switch 233 opens, however, the high part 241 of cam 239 closes switch 231 so that motor 56 continues to operate.

(c) When the feed slide 197 is again moved forward by the spring pressure of switch 233 to feed a blank onto the bedplate 17 the switch 233 again closes and immediately thereafter the low part 240 of cam 239 permits switch 231 to reopen, so that there is no interruption in the operation of motor 56 and cam shaft 53.

(d) If the blank jams in the feed mechanism during step (c), however, the feed slide 197 cannot move forward so that the lever 235 continues to hold open the switch 233. Meanwhile the cam 239 continues to rotate until its low part 240 allows the second switch 231 to open, whereupon the motor 56 ceases operation and the cam shaft 53 stops.

(e) Upon observing that the machine has stopped operating, the attendant corrects the jammed condition, the feed slide 197 resumes its forward movement, and cam shaft motor 56 resumes operation.

The grinding machine described in detail above has been used successfully for grinding ruby phonograph needle points having a length of .05 inch and a diameter of .016 inch at a rate greater than 200 per hour. Only occasional attention is necessary to perform such functions as filling the feed tube 201 with additional blanks, replacing

the work rest blade 25 when it has become worn, adjusting the various operating parts to compensate for wear, and correcting the infrequent jamming of the blank feed mechanism.

What is claimed is:

1. A grinding machine comprising, in combination, a support for a blank to be ground; feed mechanism for successively feeding blanks one at a time onto said support at a feeding station; a grinder positioned head-on to said support at a grinding station adjacent one end thereof; advancing mechanism movable longitudinally of said support toward and away from said grinder for advancing a blank from said feeding station along said support to said grinder at said grinding station; rotary means at said grinding station for rotating such blank on a fixed axis during grinding thereof; mechanism for moving such blank toward said grinder during the grinding thereof; mechanism operable to retract said grinder from said grinding station when grinding of said blank is finished, and to restore said grinder to said grinding station thereafter; mechanism for ejecting said blank from said grinding station during retraction of said grinder; and mechanism for returning said advancing mechanism to said feeding station to receive the next blank to be ground.

2. A grinding machine in accordance with claim 1, also comprising interlocked cam members cooperating with said several mechanisms for synchronously actuating said mechanisms to feed, grind, and eject said blanks automatically and successively.

3. A grinding machine in accordance with claim 2 wherein said feed mechanism for feeding blanks comprises a table; means for feeding a line of blanks end-to-end in a direction longitudinally of said support, and onto said table one at a time; a pusher movable transversely toward and away from said support, said pusher during movement toward said support pushing a blank from said table into the path of said advancing mechanism and blocking the movement of the next blank in line onto said table, said pusher during movement away from said support releasing said next blank in line for feeding onto said table; connecting means acting to connect said pusher with said advancing mechanism during movement of said advancing mechanism along said support away from said grinder, to move said pusher away from said support whereby the next blank in line is fed onto said table; releasing means for releasing said pusher from connection with said advancing mechanism after said next blank in line has been fed onto said table; and means urging said released pusher toward said support for pushing said blank into the path of said advancing mechanism while the latter is in retracted position.

4. A grinding machine in accordance with claim 3 wherein said means for feeding a line of blanks comprises a feed tube having an outlet adjacent said table in position to discharge blanks thereon, and means for applying pressure to said blanks in said tube for urging said blanks therethrough.

5. A grinding machine in accordance with claim 4 wherein said feed tube has an inlet remote from said outlet, wherein said machine also comprises an enclosure for said inlet providing a chamber adjacent thereto, wherein said means for applying pressure comprises a conduit connected into said chamber for supplying fluid under pressure thereto, and wherein said enclo-

sure is provided with access means whereby a new supply of blanks may be introduced into said tube through said inlet.

6. A grinding machine in accordance with claim 3 wherein said pusher comprises an actuator arm; wherein said connecting means is a finger on said advancing mechanism engageable with said arm, and wherein said releasing means is a cam surface cooperating with said finger and acting to release said finger from engagement with said actuator arm. 10

7. A grinding machine in accordance with claim 2 wherein said means for rotating such blank comprises a pair of driven rolls located on opposite sides of said support and rotatable on longitudinally extending axes, said rolls having opposed peripheral surfaces passing close together and to said support, said peripheral surfaces forming a throat therebetween to receive such blank. 15

8. A grinding machine in accordance with claim 7 wherein said grinder has the peripheral surface thereof passing through said throat in position to grind a point on such blank while such blank is rotated by said rolls. 20

9. A grinding machine in accordance with claim 3, also comprising an electric motor operating said interlocked cam members, first and second parallel switches in circuit with said motor, control means operable by said feed mechanism for opening and closing said first switch, and a rotating control cam for opening and closing said second switch, said control means and said control cam being so constructed and so synchronized with one another that normally said first switch is opened when said pusher moves away from said support and said second switch is held closed by said control cam while said first switch is open, and said first switch is closed when said pusher moves toward said support to feed a blank thereon and said second switch is opened by said control cam while said first switch is closed, and that when said pusher abnormally is prevented from moving toward said support at its normal time both of said switches are open simultaneously and said motor is stopped. 30

10. A grinding machine in accordance with claim 1 wherein said grinder is rotatable on an axis transverse to said longitudinal support and spaced transversely from the axis of rotation of such blank and longitudinally from said support whereby the peripheral surface of said grinder grinds a point on such blank while such blank is rotated. 35

11. A grinding machine in accordance with claim 2 wherein said mechanism for moving such blank toward said grinder during grinding thereof comprises a stop for said advancing mechanism; means urging said advancing mechanism toward said grinder; and means for moving said stop toward said grinder. 40

12. A grinding machine in accordance with claim 11 wherein said stop comprises a stationary block having a longitudinal bore therein, and a tubular member threaded to said block in alignment with said bore; said advancing mechanism passing through said bore and said tubular member, and having a shoulder adapted to abut against said tubular member; said tubular member being rotatable in one direction to move from its initial position toward said grinder to release said advancing mechanism toward said grinder, and being rotatable in the opposite direction to restore said tubular member to its initial position; and wherein said means for mov- 45

ing said stop comprises a rack driven by one of said cam members, a pinion driven by said rack, and means coupling said pinion with said tubular member for operating the latter. 50

13. A grinding machine in accordance with claim 2 wherein said mechanism for ejecting said blank from said grinding station comprises means cooperating with said advancing mechanism operable to strike said advancing mechanism a sharp longitudinally directed blow upon retraction of said grinder from said grinding station, to impel said blank from said support. 55

14. A grinding machine in accordance with claim 2, also comprising means coacting with said interlocked cam members and operable to start said rotary means upon introduction of a blank therein, and to stop said rotary means when grinding of said blank is finished. 60

15. A stylus grinding machine comprising, in combination, a longitudinally extending support for a blank to be ground; a pair of driven rolls located on opposite sides of said support and rotatable on longitudinally extending axes, said rolls having opposed peripheral surfaces passing close together and to said support for rotating such blank, said peripheral surfaces forming a throat therebetween; driving means for rotating said driven rolls around said longitudinally extending axes; a grinding wheel rotatable on an axis transverse to said longitudinal support and said longitudinal axes, said axis of said grinding wheel being spaced transversely from said axes of said rolls and longitudinally from said support, said grinding wheel having the peripheral surface thereof passing through said throat in position to grind a point on such blank while such blank is rotated by said rolls. 65

16. A stylus grinding machine in accordance with claim 15, also comprising mechanism for advancing such blank toward said grinding wheel during the grinding of said point. 70

17. A stylus grinding machine in accordance with claim 16 wherein the axis of one of said rolls is tilted to urge such blank toward said last-named mechanism, said machine also comprising means for driving one of said rolls at a greater peripheral speed than the other to hold said blank down on said support during grinding thereof. 75

18. A grinding machine comprising, in combination, a longitudinally extending support for a blank to be ground; a grinder at a grinding station adjacent one end of said support having a peripheral grinding surface extending across said support; advancing means for moving a blank along said support to said grinding station; means for rotating such blank on a fixed longitudinal axis at said grinding station; and means for moving such blank progressively further along said support during grinding thereof after initial contact with said grinding wheel. 80

19. A grinding machine in accordance with claim 18 wherein said last-named means for moving such blank progressively further along said support comprises a stationary block having a longitudinal bore therein; a tubular member threaded to said block in alignment with said bore; said advancing means passing through said bore and said tubular member, and having a shoulder adapted to abut against said tubular member; said tubular member being rotatable in one direction to move from its initial position toward said grinder, and being rotatable in the opposite direction to restore said tubular mem- 85

ber to its initial position; and means urging said advancing means toward said grinder.

20. A grinding machine comprising, in combination, a longitudinally extending support for a blank to be ground; a grinding wheel adjacent one end of said support having a peripheral grinding surface extending across said support; a push rod movable in one direction for moving a blank along said support into contact with said peripheral grinding surface; means for withdrawing said grinding wheel from its grinding position when grinding of said blank is finished; and means for moving said push rod in said same direction to eject said blank from said support after grinding thereof is finished.

21. A grinding machine comprising, in combination, a support for a blank to be ground; a pair of driven rolls rotatable on longitudinally extending axes, said rolls having opposed peripheral surfaces passing close together and forming a throat

10

20

for receiving a blank to be rotated; driving means for rotating said driven rolls around said longitudinally extending axes; a grinding wheel rotatable on an axis transverse to and spaced transversely from said first-named axes, said grinding wheel having the peripheral surface thereof passing through said throat in position to grind such blank while such blank is rotated by said rolls.

JOHN F. PELTON.
